UNITED STATES PATENT OFFICE.

SAMUEL M. VAUCLAIN, OF PHILADELPHIA, PENNSYLVANIA, ASSIGNOR TO BALDWIN LOCOMOTIVE WORKS, OF PHILADELPHIA, PENNSYLVANIA, A CORPORATION OF PENNSYLVANIA.

LOCOMOTIVE.

936,198.

Specification of Letters Patent.

Patented Oct. 5, 1909.

Application filed July 15, 1909. Serial No. 507,740.

To all whom it may concern:

Be it known that I, SAMUEL M. VAUCLAIN, a citizen of the United States, residing in Philadelphia, Pennsylvania, have invented certain Improvements in Locomotives, of which the following is a specification.

My invention relates to certain improvements in the forward frame and cylinders of a locomotive, especially of the articulated compound type, in which two frames are pivoted together; the rear frame carrying the one set of cylinders and the forward frame carrying the other set of cylinders. Heretofore, in locomotives of this type, the size of the low pressure cylinder was limited, owing to the fact that the main frame usually extended from one end of the locomotive to the other and the cylinder was made in a single piece with its saddle. By my invention I discontinue the main frame at the rear of the forward cylinders. The invention can be applied to an ordinary locomotive if desired.

The object of my invention is to increase the diameter of the cylinders without increasing the width of the locomotive, and this object I attain by discontinuing the main frame and utilizing the intermediate frame which supports the cylinders and the bumper and bumper frames, and also forms the steam passage to the said cylinders.

In the accompanying drawings:—Figure 1, is a side view of sufficient of the forward end of a locomotive to illustrate my invention; Fig. 2, is an end view looking in the direction of the arrow, Fig. 1; Fig. 3, is a transverse sectional view on the line 3—3, Fig. 5; Fig. 4, is a plan view of the cylinder and framework; the boiler being omitted; and Fig. 5, is a longitudinal sectional view on the line 5—5, Fig. 4.

In locomotives to which my invention is particularly adapted the forward and rear frames are pivoted together and the boiler is rigidly mounted on the rear frame and overhangs the forward frame. The high pressure cylinders are mounted, in the present instance, on the forward end of the rear frame and connected to the driving axles mounted in boxes on the said rear frame. The forward frame, in this instance, carries the low pressure cylinders which are

connected to axles adapted to boxes in the forward frame and the steam connections are carried from the boiler, first to the high pressure cylinders on the rear frame, then to the low pressure cylinders on the forward frame, either direct or through a re-heater. This type of engine is known as an articulated compound engine and these engines have been gradually increasing in size, but the low pressure cylinders have to be limited in diameter owing to the fact that the builders are limited to a given width.

By my invention I am enabled to keep within the width prescribed and yet increase the diameter of the cylinders without weakening the structure and without overhanging the parts beyond the limit.

A, A are two side members of the main frame of the locomotive, B, B are the low pressure cylinders, one situated on each side of the locomotive as shown, and D is an intermediate frame which is rigidly secured to the main frames A, A and the bumper frame E carrying the bumper E', to which is also firmly attached the two cylinders B, B. The frame D at the point between the cylinders is much narrower than the main frame A, consequently the cylinders can be set back nearer the center of the engine than if the main frame was continued on past the cylinders. This setting back of the cylinders enables me to considerably increase the diameter of the cylinders without increasing the width of the locomotive.

The cylinders are not provided with saddles as in the ordinary type, but have flanges b, b which are firmly bolted to flanges d on the frame D, as illustrated in Figs. 3 and 4. The bumper frame E has a reduced portion e extending between the arms D', and this bumper frame is bolted securely to these arms, as well as to the body portion of the frame D, as clearly illustrated in Figs. 4 and 5; keys e' being used at the interlocking points. The bumper E' can be made of any type desired, either of metal, as shown, or of wood.

The arms D' of the frame D extend rearwardly between the side members A, A of the main frame of the locomotive and preferably interlock with the frame; keys a' being used at the interlock. Transverse bolts firmly secure the main frame to the inter-

mediate frame D; suitable webs and braces being used to strengthen the frame so that this portion of the locomotive will be as substantial as if the main frame extended the full length of the locomotive.

In some instances I may make the intermediate frame D simply a continuation of the main frame, but I prefer to utilize it also as a means of forming communication between the steam supply pipe leading from the high pressure cylinders. This enables me to increase the strength of the frame and at the same time condense the parts so as to make the forward portion of the engine less cumbersome than heretofore.

15 G is the boiler of the locomotive and G' is the smoke box section of the boiler.

F is a pipe for supplying steam to the low pressure cylinders and is connected either directly with the high pressure cylinders or 20 indirectly through a superheater.

25 The pipe F is connected to the rear end of the frame D and has a flexible section F' which allows the forward frame of the locomotive to move independently of the boiler.

30 In the frame D is a steam passage n which communicates with the pipe F and with lateral pipes n' leading to the valve chest B' of the cylinders B, as illustrated in Fig. 3; the valves being omitted in this drawing to avoid confusion.

35 M is the exhaust pipe leading from the exhaust passages of the valve chamber B' and communicating with a pipe M' which enters the smoke box G' of the boiler. This pipe M' has a flexible section M².

40 The valve mechanism and other parts illustrated in Fig. 1, as well as the truck illustrated in Fig. 2, form no part of my present invention and, therefore, I have not described them.

45 It will be seen by the above construction that I reduce the width of the supporting frame of the locomotive. Thus I am enabled to increase the diameter of the cylinders without increasing the width of the locomotive and I utilize the intermediate frame as a passage for the steam entering the low pressure cylinders.

50 While my invention is shown especially adapted to the forward end of an articulated locomotive, it may be applied to the rear frame, or to the frame of an ordinary locomotive where it is desired to use large cylinders or to set the cylinders closer to each other than heretofore.

I claim:

1. The combination of the main frame of a locomotive, an intermediate frame coupled to the main frame and less in width than the main frame, with cylinders secured to the intermediate frame.

2. The combination of the main frame of a locomotive, an intermediate frame less in width than the main frame, and cylinders

secured to the intermediate frame at a point beyond the end of the main frame whereby the cylinders can be increased in diameter without increasing the width of the locomotive.

70

3. The combination of a main frame of a locomotive, an intermediate frame, a cylinder secured to each side of the intermediate frame beyond the end of the main frame, and a bumper frame secured to the forward 75 end of the intermediate frame.

4. The combination of a main frame of a locomotive, an intermediate frame less in width than the main frame and having rearwardly extending arms secured to the side 80 members of the main frame, said intermediate frame having forward arms, a bumper frame mounted between said forward arms and secured thereto, with a cylinder on each side of the intermediate frame beyond the 85 end of the main frame and rigidly secured to said intermediate frame.

5. The combination of a main frame, an intermediate frame less in width than the main frame, a cylinder secured to each side 90 of the intermediate frame beyond the ends of the main frame, a steam passage in said intermediate frame, and a pipe communicating with said passage, said passage also communicating with the steam chests of the cylinders.

95 6. The combination of the main frame of a locomotive, an intermediate frame less in width than the main frame and connected rigidly to the main frame and forming a 100 continuation thereof, a cylinder secured rigidly to each side of the intermediate frame, a passage in the intermediate frame, a steam supply pipe leading to said passage, branch pipes connecting said passage with the valve 105 chests of the cylinders, and a bumper casting secured to the forward end of the intermediate frame.

7. The combination of the main frame of a locomotive having two side members, each 110 side member being recessed, an intermediate frame having rearwardly projecting arms adapted to the recesses in the side members of the main frame, means for rigidly securing the intermediate frame to the side members of the main frame, said intermediate frame being less in width than the main frame, two cylinders having flanges, means for securing the flange of one cylinder to one side of the intermediate frame, means 115 for securing the flange of the other cylinder to the opposite side of the intermediate frame, a bumper frame secured to the forward end of the intermediate frame, a steam passage in the intermediate frame, a flexible steam supply pipe communicating with said steam passage in the intermediate frame, steam branch pipes forming communication between the steam space and the steam chests of the cylinders, an exhaust pipe communi- 120 125 130

cating with both steam chests, and a flexible pipe connected to the exhaust pipe and leading to the steam nozzle within the boiler.

8. The combination of the main frame of a locomotive having two side members, each member being recessed at the inner side, an intermediate frame, cylinders carried thereby and having arms adapted to the recess, wedges between the two parts, and means 10 for securing said parts together.

9. The combination of the main frame of a locomotive, an intermediate frame extending beyond the main frame and less in width than the main frame, cylinders secured to 5 the intermediate frame, the main frame be-

ing recessed and the intermediate frame having portions adapted to the recesses, wedges between the main frame and the intermediate frame, bolts securing the frames together, a bumper frame, means for securing 20 the said bumper frame to the intermediate frame, and wedges between the bumper frame and the intermediate frame.

In testimony whereof, I have signed my name to this specification, in the presence of 25 two subscribing witnesses.

SAMUEL M. VAUCLAIN.
